UNITED STATES PATENT OFFICE.

JOHN H. PINEO, OF BROOKLINE, MASSACHUSETTS.

DESIGN FOR A GUARD-ARM FOR HINGES.

SPECIFICATION forming part of Design No. 30,953, dated June 6, 1899.

Application filed May 11, 1899. Serial No. 716,446. Term of patent 3½ years.

To all whom it may concern:

Be it known that I, JOHN H. PINEO, of Brookline, in the county of Norfolk and State of Massachusetts, have invented and produced a new and original Design for Guard-Arms for Hinges, of which the following is a specification, reference being had to the accompanying drawings, forming part thereof.

In the drawings, Figure 1 represents a view of a guard-arm for hinges, illustrating my new design. Fig. 2 represents a sectional view of the same, taken on line 2 2, Fig. 1.

The leading feature of my new design for guard-arms for hinges consists in the design as herein shown and described.

As shown in the drawings, the lower end of the arm has the cylindrical shape 5, above which the shoulder 6 is formed by the enlargement of the arm 7, which curves upward and laterally from the line of the cylindrical portion, having at the upper end the oval ring-like portion 8, with the wings 9 9, which merge into the general contours of the arm. 20

What I claim is—

The design for a guard-arm for hinges as herein shown and described. 25

JOHN H. PINEO.
